UNITED STATES PATENT OFFICE.

JESSE G. VINCENT, OF DETROIT, MICHIGAN, ASSIGNOR TO BURROUGHS ADDING MACHINE COMPANY, OF DETROIT, MICHIGAN, A CORPORATION OF MICHIGAN.

ADDING-MACHINE.

No. 913,860.

Specification of Letters Patent. Patented March 2, 1909.

Application filed October 1, 1906. Serial No. 336,921.

To all whom it may concern:

Be it known that I, JESSE G. VINCENT, a citizen of the United States, residing at Detroit, in the county of Wayne and State of Michigan, have invented certain new and useful Improvements in Adding-Machines, of which the following is a specification.

The present invention relates more particularly to that type of adding and listing machine in which accumulator pinions and their actuating racks are engaged and disengaged in varying periods of the machine's operation, according to whether itemizing, total taking or subtotal taking is being done. In machines of this type it is customary when itemizing to keep the pinions and racks disengaged during the first part of the operation when the racks are being set to positions determined by depressed keys and to then bring the racks and pinions into engagement for the return movement of the racks. In taking totals the reverse order is followed, that is to say engagement between the racks and pinions is preserved during the first part of the operation. In the case of a grand total, whereby the machine is cleared, the racks and pinions are then disengaged for the return movement, but in the case of a subtotal, whereby the accumulation is preserved the racks and pinions still remain in engagement. The connection for bringing about engagement and disengagement of the racks and pinions are generally controlled by manipulative means so that the normal itemizing adjustment can be changed at will to a totalizing adjustment. It is common for the manipulation of such means to disable the connections for effecting disengagement of the racks and pinions during the first part of the machine's operation and when a grand total is to be taken automatic means come into play for disengaging the racks and pinions during the latter part of the machine's operation. For the purpose of preserving the accumulation after the total has been taken it is sufficient to simply release the manipulative means when the machine has completed the first part of its operation, because thereby the automatic means are prevented from operating to bring about disengagement of the racks and pinions.

The principal object of the present invention is to do away with the necessity for releasing the manipulative means at a certain

stage in the operation of the machine when a subtotal is desired and to provide additional manipulative means for preventing the automatic action above mentioned whereby the disengagement of the racks and pinions is brought about. It is further proposed to not only lock both manipulative means against manipulation once the machine has started upon an itemizing operation until such operation is completed, as has heretofore been done in the case of the first described manipulative means, but also to provide for locking said means against return after manipulation once the machine has started upon a totalizing operation and until that operation is completed.

Another object attained by the present invention is the provision of means for preventing adjustment of connections for taking a subtotal after manipulation has started for the taking of a grand total and vice versa.

With these and incidental objects in view, the invention consists of certain novel features of construction and combinations of parts the essential elements whereof are recited in the appended claims and a preferred form of embodiment of which is described in detail hereinafter and fully illustrated in the accompanying drawings forming part of this specification.

Of said drawing, Figure 1 represents in left side elevation the interior parts of an adding and listing machine of the well known Burroughs type with the present improvements applied thereto, the casing and certain cross shafts and studs appearing in section, as well as parts of the paper carrying attachment; Fig. 2 similarly represents on an enlarged scale the parts more particularly concerned with the present invention, the same being represented relatively positioned as when the total key has been depressed, dotted lines representing further change in relative positioning when an operation of the machine has been started; Fig. 3 is a similar view representing the relative positioning of parts when the subtotal key is depressed and Fig. 4, is a fragmentary right side elevation of the interior parts of the machine as they appear at normal.

By preference the invention has been illustrated as applied to the well known Burroughs adding machine but it is to be understood that it is applicable to other

types of machines. For a full and complete understanding of all of the details of the Burroughs machine reference may be had to the Burroughs Patents Nos. 504,963, 5 and 505,078 issued September 12, 1893, and to the Macauley Patent No. 823,474, issued June 12, 1906. It will be sufficient for the purposes of the present specification to briefly enumerate certain well known parts 10 of the Burroughs machine with which the present invention is more particularly concerned and to point out briefly the usual mode of operation of those parts. The reference numeral 291 designates the usual 15 amount keys and the numeral 610 segmental racks whose extent of movement is determined by stops set by said keys. Small gear wheels or pinions 916 are arranged to mesh with these racks respectively and are 20 compounded with numbered wheels 990 which accumulate the amounts set up on the keyboard. Said pinions and number wheels are carried in a rocking frame having end plates 910 one of which extends below 25 the pivot rod 900 and carries inwardly projecting studs or pins 958 and 958^a one above and the other below said rod. A pitman 914 is branched at the forward end for engagement with these pins or studs and at its 30 rear end connects with a three-armed lever 913 carrying studs or pins 961 arranged to be alternately acted upon by a wipe pawl 821 on the upper end of an arm 813 secured to a rock shaft 800. The latter is oscillated in 35 every operation of the machine and through the devices described the pitman is reciprocated. The latter is connected through a link 911 with a bell crank lever 227 constituting the total key and normally upheld 40 by a suitable spring 282. So long as this total key is so upheld the reciprocations of the pitman have the effect of removing the accumulator pinions from engagement with the racks at the outset of an operation of 45 the machine and then restoring said pinions to mesh with said racks after the latter have lowered to the extent permitted by depressed amount keys and before the return of said racks to normal. This is due to the fact 50 that normally the stud or pin 958^a rests in a notch of the upper branch of the pitman. Depression of the total key lowers the pitman and destroys this operative connection so that when the pitman is thrust forward 55 as the machine starts to operate the accumulator pinions remain in mesh with the racks. The lowering of the pitman in this manner brings the forward extremity of its lower branch into position for engagement 60 with the stud 958 so that when the pitman moves rearwardly it will rock the accumulator frame and disengage the pinions from the racks before the return movement of the latter commences. 65 It will be noted that the link 911 is formed

at its upper end with a longitudinal slot 911^a and that the total key lever 227 carries a screw-stud 227^a engaging said slot. This stud normally occupies the upper end of the slot and when the total lever is depressed for 70 a totalizing operation the link and pitman simply travel down with it by their own weight supplemented by a spring 981 connecting the link with the arm 813. This has the effect of bringing the hooked end 75 914^b of the lower branch of the pitman to rest upon the top of the lower stud 958, as shown in Fig. 2. When the pitman moves forward this hooked end will drop over said stud as shown by the dotted lines in Fig. 2, 80 owing to the above mentioned slot-and-pin connection between the link and the total lever. Therefore unless the lever is meantime released and permitted to rise carrying with it the link and pitman the hooked end 85 of the latter will upon the rearward movement thereof take hold of the stud 958 and rock the accumulator pinions out of mesh with the racks. In machines of the above description as heretofore employed it has 90 been customary to preserve engagement between the racks and pinions for subtotal purposes by simply releasing the total key or key lever before the rearward movement of the pitman takes place. By the present invention it is proposed to prevent the hooked end 95 of the pitman from dropping in front of the stud 958 at all when a sub-total is to be taken.

For the purposes of the present invention 100 a second total lever 227^s is employed, the same being preferably located further up the keyboard than the lever 227. This second total lever is of bell crank form; the same as the other lever, and to its depending arm 105 there is pivotally connected the rear end of a bar 216 which extends forward alongside of the depending arm of the other bell crank lever and alongside of the link 911. The forward end of this bar is slidably supported 110 upon a cross rod 202, the bar being longitudinally slotted as at 216^a to embrace said rod and furthermore notched at opposite ends of the slots in the upper side thereof, as shown at 216^b for the purpose of engaging the cross 115 rod in such manner as to detain the bar in either of its two adjustments. In furtherance of this design a spiral spring 281 connects the forward end of the bar with a fixed stud so as to enforce the engagement between 120 said notches and said cross rod. The bar 216 is formed on its under side about midway its length with a depending lug 216^c which normally stands immediately in front of a laterally projecting stud 227^c on the depending arm of the bell crank 227 as shown in Fig. 1, this arm of the bell crank being as usual drawn forward by the spring 282 which operates to uphold the link 911 and pitman 125 914. Depression of the subtotal key lever 130

227^a has the effect of drawing rearwardly the bar 216 and through the action of the lug 216^c upon the stud 227^c of depressing the total lever and causing lowering of the link 911 and of the pitman as illustrated in Fig. 3. This is practically the same effect produced by direct depression of the total lever 227, the difference being that the hooked end of the pitman does not come to rest upon the stud 958 and the pitman is prevented from dropping so as to engage the front side of said stud. This is accomplished as follows: The link 911 carries a laterally projecting stud 950 a short distance below the slot 911^a and the bar 216 at the forward portion is adapted to pass under said stud when the bar moves rearwardly, thereby preventing the automatic dropping of the link and pitman such as otherwise permitted by the slot-and-pin connection before mentioned. This particular part of the bar terminates in an abrupt transverse shoulder 216^d, the bar being notched immediately behind said shoulder to receive the stud 950 when the total lever is directly depressed, see dotted lines Fig. 2. It will be seen that the lowering of the link by direct depression of the total lever 227 results in locking the subtotal lever against depression by reason of the stud 950 taking up a position in rear of the shoulder 216^d. Of course such depression of the total lever has no effect to move the subtotal lever, the stud 227^c simply retreating from the lug 216^c.

The above described arrangement will be seen to do away with release of the total key lever at an intermediate stage of the machine's operation when a subtotal is to be taken. Consequently this lever can be locked down during the entire operation of the machine and does not require to be held down by the operator. To this end the familiar oscillatory sector 311 of the Burroughs machine (Fig. 4) carries on one side a curved locking strip 315 and the well known rock shaft 1400 carries a depending arm 1414 equipped at its lower end with a roller-stud 1435 normally standing just beyond the forward end of the lock strip 315 on the inner side thereof. A short crank arm 1410 on the rock shaft 1400 is connected by a link 1416 with the depending arm of the bell crank lever 227 or with a companion arm 227^b at the opposite side of the machine and it will be seen that the rocking of this lever when setting the parts for taking either a total or subtotal will result in carrying the roller-stud 1435 across the end of the lock strip 315 to the front side of the latter. Upon the machine's starting to operate the lock strip is instantly carried behind the roller stud and it is made sufficiently long to remain behind said stud when the sector 311 reaches the limit of its initial stroke. Consequently the total connections will remain locked until the sector returns to normal.

Obviously when neither total key is depressed and the machine is operated the lock strip passes in front of the roller stud, remaining there throughout the operation of the machine and preventing any manipulation of either total key. 70

The total levers are preferably operated by means of key buttons 293 and 293^a mounted respectively upon stems forming parts of the levers and arranged to slide 75 through the keyboard plates. The bell crank 227 as usual operates a bail comprising side arms 226 and a cross rod 226^a for displacing the rack latches 415.

It will now be seen that the above described constructions are well calculated to thoroughly fulfil the objects primarily stated. At the same time it is to be understood that these constructions are susceptible of modification, the invention not being 85 limited to the details thereof.

What is claimed is:

1. In a machine of the character described, the combination of an accumulator and actuator relatively movable for engagement and disengagement, manipulative means for preserving engagement between said parts for backward movement of the accumulator to zero in total taking, means dependent thereon for automatically establishing connections to disengage the accumulator and actuator for the purpose of leaving the former at zero, and separately manipulative means for actuating the first mentioned manipulative means to preserve engagement between accumulator and actuator but preventing operation of said automatic means and thereby continuing the engagement for the purpose of restoring the accumulation after the movement to zero. 105

2. In a machine of the character described, the combination of an accumulator and actuator relatively movable for engagement and disengagement, manipulative means for preserving engagement between 110 said parts for backward movement of the accumulator to zero in total taking, means dependent thereon for automatically establishing connections to disengage the accumulator and actuator for the purpose of leaving the former at zero, separately manipulative means for similarly preserving engagement between accumulator and actuator but preventing operation of said automatic means and thereby continuing the engagement for 120 the purpose of restoring the accumulation after the movement to zero and means for locking the first-mentioned manipulative means in operated position during substantially the entire operation of the machine. 125

3. In a machine of the character described, the combination of an accumulator and actuator relatively movable for engagement and disengagement, manipulative means for preserving engagement between 130

said parts for backward movement of the accumulator to zero in total taking, means dependent thereon for automatically establishing connections to disengage the accumulator and actuator for the purpose of leaving the former at zero, separately manipulative means for similarly preserving engagement between accumulator and actuator but preventing operation of said automatic means 10 and thereby continuing the engagement for the purpose of restoring the accumulation after the movement to zero and means for locking the first-mentioned manipulative means in operated or unoperated position 15 during substantially the entire operation of the machine.

4. In a machine of the character described, the combination of an accumulator and actuator relatively movable for engagement and 20 disengagement, manipulative means for preserving engagement between said parts for backward movement of the accumulator to zero in total taking, means dependent thereon for automatically establishing connections to disengage the accumulator and actuator for the purpose of leaving the former at zero, separately manipulative means for similarly preserving engagement between accumulator and actuator but preventing 25 operation of said automatic means and thereby continuing the engagement for the purpose of restoring the accumulation after the movement to zero and means for locking both manipulative means in unoperated 30 position during substantially the entire operation of the machine.

5. In a machine of the character described, the combination of an accumulator and actuator relatively movable for engagement and 40 disengagement, manipulative means for preserving engagement between said parts for backward movement of the accumulator to zero in total taking, means dependent thereon for automatically establishing connections to disengage the accumulator and actuator for the purpose of leaving the former at zero, separately manipulative means for similarly preserving engagement between accumulator and actuator but preventing 45 operation of said automatic means and thereby continuing the engagement for the purpose of restoring the accumulation after the movement to zero and means for locking one manipulative means by the other.

55 6. In a machine of the character described, the combination of reciprocating racks, accumulator pinions normally in mesh therewith, a carrier for said pinions movable to disengage the same from the racks, connections for shifting the carrier adjustable to vary the periods of engagement between pinions and racks, manipulative means for disabling the itemizing connection which primarily disengages the racks and pinions, 60 provisions for automatically effecting a

grand totalizing connection for producing disengagement after return to zero, and separately manipulative means for actuating the first mentioned manipulative means to disable the itemizing connection and prevent 70 operation of said automatic means.

7. In a machine of the character described, the combination of reciprocating racks, accumulator pinions normally in mesh therewith, a pivoted carrier for said pinions movable to disengage the same from the racks, a pitman normally engaging said carrier on one side of its pivot to move it back and forth but adjustable to engage the carrier on the other side of its pivot to move it in one 80 direction, manipulative means connected to said pitman for disengaging it from the pinion-carrier on the first-mentioned side of the latter's pivot with provisions for effecting automatic engagement on the opposite 85 side of the pivot, and separately manipulative means for producing the same disengagement between pitman and carrier but preventing the automatic reengagement on the opposite side of the pivot. 90

8. In a machine of the character described, the combination of reciprocating racks, accumulator pinions normally in mesh therewith, a pivoted carrier for said pinions movable to disengage the same from the racks 95 and having studs on opposite sides of its pivot, a laterally movable pitman having a notched branch normally embracing one of said studs and an oppositely extending branch for engagement with the other stud 100 but normally removed therefrom, manipulative means connected to said pitman for disengaging its notched branch from the associated stud with provisions for automatically effecting operative engagement 105 between the other branch and stud, and separately manipulative means for effecting disengagement between the notched branch and associated stud while preventing the automatic engagement between the other 110 branch and stud.

9. In a machine of the character described, the combination of reciprocating racks, accumulator pinions, normally in mesh therewith, a pivoted carrier for said pinions movable to disengage the same from the rack and having studs on opposite sides of its pivot, a laterally movable pitman having a notched branch normally embracing one of said studs and an oppositely extending 120 branch for engagement with the other stud but normally removed therefrom, said pitman tending to disengage its notched branch from the associated stud, manipulative means normally restraining the pitman from 125 such disengaging movement and connected thereto with provisions for permitting its independent movement to automatically engage its other branch with the other stud, and separately manipulative means for per- 130

mitting the disengagement of the notched branch of the pitman from the associated stud while preventing the automatic independent movement of the pitman.

- 5 10. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch 70
15 hooked for engagement with the lower stud but normally elevated above the same, said pitman tending to drop disengaging its notched branch from the associated stud and bringing its hooked branch to rest upon the 75
20 lower stud, manipulative means normally upholding the pitman and connected thereto with provisions for permitting its lowering beyond the point to which manipulation of said means carries it thereby causing effective engagement between its lower branch and the lower stud, and separately manipulative means for permitting the same disengaging movement of the pitman but preventing the effective engagement thereof 80
25 30 with the lower stud.

11. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same 95
35 and an oppositely extending branch hooked for engagement with the lower stud but normally elevated above the same, said pitman tending to drop disengaging its notched branch from the associated stud and bringing its hooked branch to rest upon the lower 100
40 stud, a link connected at one end with said pitman, a normally upheld total key lever having a slot and pin connection with said link and equipped for direct depression to cause lowering of the link and consequent 105
45 disengagement of the notched branch thereof from the upper stud leaving the link and pitman free to drop further as permitted by the slot and pin connection and effectively engage its hooked branch with the lower 110
50 stud, a separate depressible sub-total key lever, and a bar connected therewith and engaging the said total key lever to depress the same, said bar adapted to engage the link and prevent the slot-and-pin drop of 115
55 the pitman.

12. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman 120
60
65

tending to drop disengaging its notched branch from the associated stud and bringing its hooked branch to rest upon the lower stud, a link connected at one end with said pitman, a normally upheld total key lever 70
75 having a slot and pin connection with said link and equipped for direct depression to cause lowering of the link and consequent disengagement of the notched branch thereof from the upper stud leaving the link and pitman free to drop further as permitted by the slot and pin connection and effectively engage its hooked branch with the lower stud, and a separate key lever connected with the said total key lever and depressible to operate the latter for effecting disengagement of the notched branch of the pitman from the upper stud, said separate key lever having means for preventing the slot-and-pin drop of the pitman. 80
85

13. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked 90
95 for engagement with the lower stud but normally elevated above the same, said pitman tending to drop disengaging its notched branch from the associated stud and bringing its hooked branch to rest upon the lower 100
105 stud, a link connected at one end with said pitman, a normally upheld total key lever having a slot and pin connection with said link and equipped for direct depression to cause lowering of the link and consequent disengagement of the notched branch thereof from the upper stud leaving the link and pitman free to drop further as permitted by the slot and pin connection and effectively engage its hooked branch with the lower 110
115 stud, a separate depressible sub-total key lever, and a bar connected therewith and engaging the said total key lever to depress the same, said bar adapted to engage the link and prevent the slot-and-pin drop of 120
125 the pitman.

14. In a machine of the character described, the combination of vertically reciprocating racks, accumulator pinions normally in mesh therewith, a pivoted carrier 120
125 for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman tending to drop disengaging its notched branch from the associated stud 130

- and bringing its hooked branch to rest upon the lower stud, a link connected at one end with said pitman and having a laterally projecting stud or pin, a normally upheld total key lever having a slot and pin connection with said link and equipped for direct depression to cause lowering of the link and consequent disengagement of the notched branch thereof from the upper stud leaving the link and pitman free to drop further as permitted by the slot and pin connection and effectively engage its hooked branch with the lower stud, a separate depressible sub-total key lever, and a shouldered bar connected therewith and engaging the said total key lever to depress the same, the link stud normally standing above and beyond the shoulder of the bar but adapted upon direct depression of the total key lever to pass down along said shoulder and prevent movement of the bar whereas when the sub-total key lever is depressed the bar is drawn under said link stud to prevent the slot-and-pin drop of the pitman.
15. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman tending to drop disengaging its notched branch from the associated stud and bringing its hooked branch to rest upon the lower stud, a link connected at one end with said pitman, a normally upheld total key lever of bell crank form having a slot and pin connection with said link and equipped for direct depression to cause lowering of the link and consequent disengagement of the notched branch thereof from the upper stud leaving the link and pitman free to drop further as permitted by the slot and pin connection and effectively engage its hooked branch with the lower stud, a separate depressible sub-total key lever of bell crank form, and a bar connected therewith and engaging the said total key lever to depress the same, said bar adapted to engage the link and prevent the slot-and-pin drop of the pitman.
16. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman tending to drop disengaging its notched branch from the associated stud and bringing its hooked branch to rest upon the lower stud, a link connected at one end with said pitman, a normally upheld total key lever of bell crank form having a slot and pin connection with said link and equipped for direct depression to cause lowering of the link and consequent disengagement of the notched branch thereof from the upper stud leaving the link and pitman free to drop further as permitted by the slot and pin connection and effectively engage its hooked branch with the lower stud, a separate depressible sub-total key lever of bell crank form, and a bar connected therewith and having a lug engaging the stud of the total key-lever, said bar adapted to engage the link and prevent the slot-and-pin drop of the pitman.
17. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman tending to drop disengaging its notched branch from the associated stud and bringing its hooked branch to rest upon the lower stud, a link connected at one end with said pitman, a normally upheld total key lever of bell crank form having a slot and pin connection with said link and provided with a laterally projecting stud and equipped for direct depression to cause lowering of the link and consequent disengagement of the notched branch thereof from the upper stud of the carrier leaving the link and pitman free to drop further as permitted by the slot and pin connection and effectively engage its hooked branch with the lower stud of said carrier, a separate depressible sub-total key lever of bell crank form, and a bar connected therewith and having a lug engaging the stud of the total key-lever, said bar adapted to engage the link and prevent the slot-and-pin drop of the pitman.
18. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same

and an oppositely extending branch hooked for engagement with the lower stud but normally elevated above the same, said pitman tending to drop disengaging its notched 5 branch from the associated stud and bringing its hooked branch to rest upon the lower stud, a link connected at one end with said pitman and having a laterally projecting stud or pin, a normally upheld total key lever 10 of bell crank form having a slot and pin connection with said link and provided with a laterally projecting stud and equipped for direct depression to cause lowering of the link and consequent disengagement of the 15 notched branch thereof from the upper stud of the carrier leaving the link and pitman free to drop further as permitted by the slot and pin connection and effectively engage its hooked branch with the lower stud of the 20 carrier, a separate depressible sub-total key lever of bell crank form, and a shouldered bar connected therewith and having a lug engaging the stud of the total key-lever, the link stud normally standing above and beyond the shoulder of the bar but adapted 25 upon direct depression of the total key lever to pass down along said shoulder and prevent movement of the bar whereas when the sub-total key lever is depressed the bar is drawn under said link stud to prevent the slot-and-pin drop of the pitman.

19. In a machine of the character described, the combination of vertically reciprocating racks, accumulator pinions normally in mesh therewith, a pivoted carrier for said pinions having studs above and below its pivot, a vertically movable and horizontally reciprocating pitman having a branch notched for engagement with the upper stud and normally embracing the same and an oppositely extending branch hooked for engagement with the lower stud but normally elevated above the same, said pitman tending to drop disengaging its notched 40 branch from the associated stud and bringing its hooked branch to rest upon the lower stud, a link connected at one end with said pitman, a normally upheld total key lever of bell crank form having a slot and pin connec-

tion with said link and equipped for direct depression to cause lowering of the link and consequent disengagement of the notched branch thereof from the upper stud leaving the link and pitman free to drop further as permitted by the slot and pin connection and effectively engage its hooked branch with the lower stud, a separate key lever of bell crank form connected with the said total key lever and depressible to operate the latter for effecting disengagement of the notched branch 55 of the pitman from the upper stud, said separate key lever having means for preventing the slot-and-pin drop of the pitman, an oscillatory prime mover carrying a lock strip, a vibratory arm having a laterally projecting 60 stud standing normally beyond one end of the lock-strip to one side of the latter and adapted to move across that end to the other side of the strip, and a link connecting said arm with the total key lever, the lock strip 65 being sufficiently long to remain in locking engagement with the arm-stud while the prime mover oscillates back and forth under either adjustment of the arm.

20. In a machine of the character described, the combination with accumulating and totaling and subtotaling mechanism; of separately manipulative means, the one to cause the taking of a total and the other to cause the taking of a subtotal, and a lock 70 common to both means for holding either in operative position throughout a totaling or subtotaling operation.

21. In a machine of the character described, the combination with accumulating, totaling and subtotaling mechanism; of separately manipulative means, the one to cause the taking of a total and the other to cause the taking of a subtotal, and a lock common to both means for holding either in operative 80 position throughout a totaling or subtotaling operation, said lock also operating to prevent operation of either of said means after an accumulating operation has started.
